(57) **CLAIM**

The ornamental design for a patty forming device, as shown and described.

DESCRIPTION

FIG. 1 is a perspective view showing the patty forming device of the present invention and the parts in their closed position.

FIG. 2 is a top plan view.

FIG. 3 is a lefthand side view. The right hand side view being a mirror image thereof.

FIG. 4 is a rear view.

FIG. 5 is a front view.

FIG. 6 is a bottom view; and,

FIG. 7 is a perspective view similar to FIG. 1, but showing the apparatus in its fully open position.
